UNITED STATES PATENT OFFICE.

LOUIS WOJIDKOW, OF BROOKLYN, NEW YORK.

DESIGN FOR A PLATE OR SIMILAR ARTICLE.

SPECIFICATION forming part of Design No. 28,094, dated December 28, 1897.

Application filed October 20, 1897. Serial No. 655,858. Term of patent 3½ years.

To all whom it may concern:

Be it known that I, LOUIS WOJIDKOW, a citizen of the United States, residing at Brooklyn, county of Kings, and State of New York, have invented and produced a new and original Design for a Plate or Similar Article, of which the following is a specification, reference being had to the accompanying drawings, forming part thereof.

10. Figure 1 is a plan view of a plate or similar article showing my new design, and Fig. 2 is a transverse section thereof.

As shown in the drawings, the leading or material feature of my design consists of a 15 plate or similar article the rim of which is scalloped and beaded.

A indicates the plate or body, the rim of which is continuously ornamented by means of scallops B, the edges of which scallops are

provided with a continuous beaded border C, 20 consisting of balls or bulbs which protrude both above and below the edge of the plate or body. The plate or body can, it is manifest, be engraved or otherwise ornamented as desired.

Having described my invention, what I claim as new, and desire to secure by Letters Patent, is—

The design for a plate or similar article, substantially as herein shown and described. 30

In testimony that I claim the foregoing as my invention I have signed my name in presence of two subscribing witnesses.

LOUIS WOJIDKOW.
